(57) **CLAIM**

The ornamental design for an electric vehicle charger, as shown and described.

DESCRIPTION

FIG. 1 is a left front perspective view of my new design for an electric vehicle charger;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof;

FIG. 8 is an enlarged view of a portion of FIG. 1;

FIG. 9 is an enlarged view of a portion of FIG. 2;

FIG. 10 is an enlarged view of a portion of FIG. 4;

FIG. 11 is an enlarged view of a portion of FIG. 6; and,

FIG. 12 is an enlarged view of a portion of FIG. 1.

The portions of the electric vehicle charger shown in broken lines form no part of the claimed design.
